UNITED STATES PATENT OFFICE.

ALFRED W. F. GUEST, OF BROOKLYN, NEW YORK, ASSIGNOR TO MERGENTHALER LINOTYPE COMPANY, A CORPORATION OF NEW YORK.

TYPOGRAPHICAL COMPOSING AND CASTING MACHINE.

Application filed April 16, 1923. Serial No. 632,233.

To all whom it may concern:

Be it known that I, ALFRED W. F. GUEST, a citizen of the United States, residing at Brooklyn, in the county of Kings and State of New York, have invented certain new and useful Improvements in Typographical Composing and Casting Machines, of which the following is a specification, reference being had therein to the accompanying drawing.

This invention relates to typographical machines, such as linotype machines of the general organization presented in Letters Patent of the United States to O. Mergenthaler, No. 436,532, wherein circulating matrices are released from a magazine in the order in which their characters are to appear in print and then composed in line in an "assembling elevator," the composed line then transferred through an intermediate channel into a vertically movable "first elevator" which presents it to a mold, whereupon the mold is filled with molten metal to form a slug or linotype against the matrices which produce the type characters thereon, and the matrices thereafter elevated and returned through a distributing mechanism to the magazine from which they started. More particularly, it relates to that class of machines designed to handle matrices provided with two or more superposed characters, and wherein the assembling elevator, intermediate channel, and first elevator are each provided with two sets of supporting rails whereby the matrices may be composed and maintained at an upper or lower level, or both, as desired, to locate the selected characters in operative position.

When it is desired to cast a slug from the lower characters of all of the matrices of a composed line (as for a "solid" line of italics), it is the usual practice to assemble and maintain such matrices, not at the upper level as would otherwise be required, but at the lower level, and then to arrest the first elevator in a slightly raised position so as to locate the selected characters opposite the mold slot, such arrest of the elevator being ordinarily effected by a stop member mounted on the vise frame and adapted to be thrown into action at the will of the operator. Similarly, in the use of "head-letter" matrices or matrices with characters above 14 pt. the same practice is followed so as to effect the proper alinement of the matrix

characters with the mold slot. The foregoing practice has given rise to very serious objections, as it frequently happens that an operator, through oversight or carelessness, will assemble matrices at the upper level while the elevator stop is in action, which will result in the improper presentation of the matrix line to the mold and hence produce a "squirt," or cause damage to the parts, or both.

The present invention is intended to overcome the above objection and aims to prevent the casting operation except under the proper conditions. To this end, the machine is equipped with a safety device which acts when the elevator stop is in active position to arrest the operation of the machine unless the matrices are composed at the lower level, as required. In the embodiment herein illustrated, the safety device is in the form of a pivoted lever mounted on the vise frame and carrying at one end an interponent which in one position will permit the operation by the first elevator of the well known "vise automatic" but which in another position will prevent such operation of the vise automatic and thereby bring about the disengagement of the main driving clutch of the machine. The position of the interponent is controlled by that of the adjustable supporting blade of the assembling elevator which controls the level at which the matrices are composed. In other words, when the matrix supporting blade of the assembling elevator is withdrawn to inactive position, so as to permit the matrices to be composed at the lower level, then the interponent may occupy its inactive position so as to permit the depression of the vise automatic by the first elevator, whether the latter is arrested in a raised position or allowed to descend to its normal position; but when the matrix supporting blade of the assembling elevator is projected thereinto or is in active position, as required for the composition of the matrices at the upper level, then the safety device is actuated to locate its interponent in position to prevent the depression of the vise automatic by the first elevator in case the stop or filler piece is at the time in active position for the arrest of the first elevator in raised condition. In this way, the casting operation is permitted or prevented according to the relative adjustment of the matrix

supporting blade of the assembling elevator and the stop or filler piece for the first elevator.

In the accompanying drawing, the present embodiment is shown merely by way of example and in preferred form and as applied to the specific kind of machine mentioned, but obviously many changes and variations may be made therein without departing from the spirit of the invention, which, it is therefore to be understood, is not limited to any specific form or embodiment except in so far as such limitations are specified in the claims.

15 Referring to the drawing:

Figure 1 is a perspective view showing by full and dotted lines, a portion of a linotype machine equipped with the present improvement; and

20 Fig. 2 is a vertical section taken through the casting mechanism, and showing the parts in the relative positions they occupy when the improved safety device is in action.

The matrices X (herein shown as of the 25 two-letter variety) are composed in line within the assembler or assembling elevator A, in the usual way. After composition of the line, the elevator A is raised into registration with the intermediate channel B, 30 through which the line is transferred into the transporter or first elevator C. The first elevator then descends to locate the composed line before the casting mold D, which immediately advances from the rear into engagement with the line for the casting operation, the lower ears of the matrices engaging in one or the other of the aligning grooves D¹ and D² according to the level at 35 which they are located. The assembling elevator A is formed with a pair of fixed matrix supporting rails A¹ and with an adjustable matrix supporting rail A², the adjustment of the latter being effected by means of a handle A⁴ fast to a rock shaft A³ carried by 40 the elevator and connected to the rail through arms A⁵. The adjustable rail A² thus determines the level at which the matrices are composed in line, said rail acting when in active position to sustain the 45 matrices at the upper level and when in inactive position to allow them to pass to the lower level where they are sustained by the fixed rails A¹. The first elevator C (Fig. 2) is likewise formed with a pair of fixed rails 50 C¹ to sustain the matrices at the lower level and with a retractable rail C² to sustain them at the upper level. The intermediate channel B is formed with two pairs of fixed rails B¹ and B², respectively, which serve to 55 maintain the matrices at their composed levels during the transfer of the line from one elevator to the other. The foregoing parts are well known, but if further information is desired, reference may be had to 60 the Rogers Reissue Patent No. 13,489.

In the normal operation of the machine, the first elevator C is allowed to descend to its lowermost position, as determined by the engagement of its set screw C³ with the top of the vise frame G. In this connection, it is pointed out that the elevator is also provided with a second set screw C⁴ arranged to engage and depress the so-called "vise-automatic" G¹ as the elevator comes to rest. The operation of the vise-automatic is fully described in the Mergenthaler Patent No. 436,532 before referred to, so that no detailed description thereof seems necessary, but it may be noted that unless it is depressed by the first elevator, the operation of the machine will be arrested almost immediately and the casting operation thereby prevented, due to the automatic disengagement of the main driving clutch.

For reasons previously noted, it is sometimes desired to arrest the first elevator in a raised position with reference to the mold, and this may be effected, as customary, by means of a stop or filler piece E pivoted to a block E¹ on the vise frame G so as to be swung into or out of active position. At its free end, the stop is provided with two contact pieces E² and E⁴, the former being carried directly by the body portion of the stop and adapted to cooperate with the set screw C³ in limiting the descent of the elevator, and the latter being carried by a hinged flap or section E² and adapted to cooperate with the set screw C⁴ in depressing the vise automatic G¹. In Fig. 1, the stop or filler piece E is shown in active position and hence will bring about the arrest of the first elevator in its raised position, as well as the depression of the vise-automatic G¹, in the usual way. When the elevator is thus arrested, it is necessary that the matrices stand at the lower level, as otherwise the objections before mentioned will arise. Thus, if matrices were standing at the upper level, as in Fig. 2, it is evident that their lower ears would fail to enter the upper aligning groove D¹ of the mold D as the latter advances from the rear, so that injury to the parts or a "squirt" would necessarily result.

According to the present invention, and to obviate the foregoing objection, means are provided to stop the machine before the advance of the mold and before the casting operation, unless the matrices are standing at a lower level when the first elevator is to be arrested in its raised position. To accomplish this result, the machine is equipped with a safety device which is controlled in such manner as to bring about such stoppage of the machine when both the elevator stop E and the assembler rail A² are in active position. In the exemplary embodiment herein illustrated, the safety device is in the form of a long L-shaped lever F intermediately pivoted, as at F¹, to the vise

frame G. At one end, the lever is provided with an interponent F², adapted in one position of the lever to stand clear of the contact piece E⁴ (Fig. 1), and adapted in the other position of the lever to fill the space between said contact piece and the vise frame (Fig. 2), it being noted that the interponent F² is beveled at one side to facilitate its entrance beneath the contact piece E⁴ and that it is also notched to clear the upper end of the vice-automatic G¹. The opposite end of the lever F is arranged to be acted upon by a centrally pivoted short lever F³ mounted upon a supporting bracket F⁴ on the intermediate channel B and arranged to be acted upon in turn by an upright arm F⁵ fast to the assembler rock shaft A³. It will now be seen that, when the assembler rail A² is in inactive position so as to permit the matrices to be composed at the lower level, the interponent F² stands clear of the contact piece E⁴ and hence will permit the machine to operate in the usual way. When, however, the assembler rail A² is adjusted to active position for the composition of the matrices at the upper level, the arm F⁵ acts upon the short lever F³ and through it actuates the long lever F so as to locate the interponent F² beneath the contact piece E⁴. Under these conditions, when the first elevator descends, it will be arrested by the engagement of its set screw C⁴ with the contact piece E⁴, which latter, instead of being allowed to yield to depress the vise-automatic G¹, is rigidly supported upon the interponent F² and thereby prevented from depressing said vise-automatic. As a result, the operation of the machine is immediately arrested and the casting and other devices brought to rest, thus avoiding any danger of a squirt or injury to the parts. As will be apparent, the safety device becomes operative only when the first elevator stop E and the assembler rail A² are both in active position. If either is in inactive position while the other is in active position, there is no danger to be avoided and the parts are allowed to operate in the usual manner. For instance, if the stop or filler piece is thrown back out of the way so as to permit the first elevator to descend to its normal position, the safety device will not function whether actuated or not by the adjustment of the assembler rail; or even if the stop is set to arrest the first elevator in raised position, the safety device will not function so long as the assembler rail is maintained in inactive position.

As before stated, the present invention has been shown merely in preferred form and by way of example and as applied to the specific kind of machine mentioned, but it is obvious that many alterations and modifications will readily suggest themselves to those skilled in the art and still be comprised

within the scope of the invention. For instance, the particular form or arrangement of the safety device or of the cooperating parts might be varied in many ways without affecting the principle or essential mode of operation involved. Moreover, in the broader aspects of the invention, the safety device, instead of bringing about the stoppage of the entire machine, might be made merely to prevent the casting operation, as by locking the pump plunger under the conditions stated. It should be understood, therefore, that the invention is not limited to any specific form or embodiment except in so far as such limitations are specified in the claims.

Having thus described my invention, its construction and mode of operation, what I claim is, as follows:

1. In a typographical composing and casting machine, the combination of means for composing matrices at different levels, means for presenting the composed matrices at different levels to the mold, and automatic means for arresting the operation of the machine after it has been initiated when the matrices are composed at a level in conflict with that at which they are presented to the mold.

2. In a typographical composing and casting machine, the combination of an adjustable member to determine the level at which the matrices are composed, an adjustable member to determine the level at which the composed matrices are presented to the mold, and automatic means actuated by the first-mentioned member to prevent the casting operation in the event of the improper relative adjustment of the two said members.

3. In a typographical composing and casting machine, the combination of an adjustable member to determine the level at which the matrices are composed, an adjustable member to determine the level at which the composed matrices are presented to the mold, and automatic means actuated by the first-mentioned member for arresting the operation of the machine in the event of the improper relative adjustment of the two said members.

4. In a typographical composing and casting machine, the combination of an adjustable member to determine the level at which the matrices are composed, an adjustable member to determine the level at which the composed matrices are presented to the mold, and a safety device actuated by the first mentioned member and controlling the operation of the machine in accordance with the relative adjustment of the two said members.

5. In a typographical composing and casting machine, the combination of an assembler wherein the matrices are composed in line at different levels and provided with

an adjustable member to determine the level of composition, a vertically movable transporter adapted to receive the composed matrices from the assembler and present them to the mold, an adjustable member to determine the vertical position of the transporter with reference to the mold, an automatic device governing the casting operation, and a safety device operative during the presenting movement of the transporter for controlling the operation of said automatic device in accordance with the relative adjustment of the two said members.

6. In a typographical composing and casting machine, the combination of an assembler wherein the matrices are composed in line at different levels and provided with an adjustable member to determine the level of composition, a vertically movable transporter adapted to receive the composed matrices from the assembler and present them to the mold, an adjustable member to determine the vertical position of the transporter with reference to the mold, an automatic device for disengaging the main driving clutch of the machine, and a safety device operative during the presenting movement of the transporter for controlling the operation of said automatic device in accordance with the relative adjustment of the two said members.

7. In a typographical composing and casting machine, the combination of an assembler provided with a matrix supporting rail adjustable to active or inactive position, a vertically movable transporter adapted to receive the composed matrices from the assembler and present them to the mold, a stop or filler piece adjustable to active or inactive position so as to arrest said transporter in raised position or permit it to descend to its normal position, and automatic means operating while the machine is in operation for preventing the casting operation when both the matrix supporting rail and the stop or filler piece are in active position.

8. In a typographical composing and casting machine, the combination of an assembler provided with a matrix supporting rail

adjustable to active or inactive position, a vertically movable transporter adapted to receive the composed matrices from the assembler and present them to the mold, a stop or filler piece adjustable to active or inactive position so as to arrest said transporter in raised position or permit it to descend to its normal position, and automatic means for arresting the operation of the machine after it has been initiated when both the matrix supporting rail and the stop or filler piece are in active position.

9. In a typographical composing and casting machine, the combination of an assembler provided with a matrix supporting rail adjustable to active or inactive position, a vertically movable transporter adapted to receive the composed matrices from the assembler and present them to the mold, a stop or filler piece adjustable to active or inactive position so as to arrest said transporter in raised position or permit it to descend to its normal position, an automatic stop device adapted to be actuated by the transporter, and a safety device acting to prevent the actuation of the automatic device when both the matrix supporting rail and the stop or filler piece are in active position.

10. In a linotype machine, the combination of the assembler A provided with the matrix supporting rail A², the first elevator C, the stop or filler piece E provided with the movable flap E², the vise-automatic G¹, and the safety device F arranged to prevent the operation of the vise-automatic when both the stop or filler piece and the matrix supporting rail are in use.

11. In a linotype machine, the combination of the assembler A provided with the matrix supporting rail A², the first elevator C, the adjustable stop or filler piece E provided with the movable flap E², the vise-automatic G¹, and the safety device consisting of the lever F carrying the interponent F², the second lever F³, and the arm F⁵, all substantially as shown and described.

In testimony whereof, I have affixed my signature hereto.

ALFRED W. F. GUEST.
